UNITED STATES PATENT OFFICE.

REINHART VICTOR WAGNER, OF LONDON, ENGLAND, ASSIGNOR TO THE WAGNER TYRE COMPANY, LIMITED, OF LONDON, ENGLAND.

RESILIENT TIRE.

1,249,695.

Specification of Letters Patent. Patented Dec. 11, 1917.

Application filed January 10, 1914. Serial No. 811,363.

To all whom it may concern:

Be it known that I, REINHART VICTOR WAGNER, a subject of the German Emperor, residing at, 33 Brooke street, Holborn, in the city and county of London, England, have invented certain new and useful Improvements in Resilient Tires, of which the following is a specification.

This invention relates to the construction of resilient wheels especially for use on vehicles, of the type in which an inner rim is suspended in an outer elastic rim.

One of the objects of the invention is to provide flexible connections between the rims possessing properties of smooth or continuous flexibility without liability of breakage. A further object is to provide means for affording transverse support to the elastic rim.

In order that the said invention may be clearly understood and readily carried into effect the same will now be described more fully with reference to the accompanying drawings, in which:

Figure 1 is a side elevation of a wheel made according to my invention, showing diagrammatically the action of the resilient rim, the side plates being moved.

Fig. 1^a is a transverse sectional view thereof.

Fig. 2 is a cross section of a wheel rim constructed according to my invention, being a slight modification.

Fig. 3 is a side view and Fig. 4 a cross section of a rim of modified construction, the section of Fig. 4 being taken on the line 4—4 Fig. 3.

Figs. 5 and 6 are respectively a cross section and a side elevation showing a further modification; and

Figs. 7 and 8 show two modifications of the method of building up the elastic rim.

A is the elastic laminated rim, which is similar throughout all parts of its circumference except for such inappreciable inequalities as may be due to the ends of the metal coils or wires from which the rim is usually built up, so that no obstructions are allowed which would affect the even

running of the wheel. B is the inner rim or wheel body made rigid and carried by the spokes b. C, C are the flexible connections between the two rims. D is the tread or tire, made of any suitable or desired material.

Figs. 1 and 2 show the general action of the wheel. It will be seen that at the lower side which meets the ground a portion of the rim A is flattened somewhat, the rim merging into the circular form a short distance on each side of the vertical. The distortion or flattening of the rim (which is somewhat exaggerated in the drawing) is thus confined to a short portion and travels around the rim as the wheel turns. The flexible connections C are constructed in any preferred manner, and, as indicated in the drawings, are relaxed at the flattened part of the rim and their tension is correspondingly increased at the sides and top in order to support the weight of the vehicle. The rim A is thus held positively to the inner rim B at all points of its circumference excepting that part temporarily under compression and the whole of the rim A is always utilized in affording support and absorbing shock. The laminations of the rim A are bound together by clips a' which inclose the same, said clips being provided with members C' to engage the flexible connections C. The rim B is provided with adjustable devices b' having members b' with which the connections C are also engaged, as more clearly illustrated in Fig. 3.

The connections C may be engaged with adjustable devices, as illustrated in Fig. 3, or they may be engaged with non-adjustable devices as illustrated in Figs. 2, 4 and 5.

Referring to Fig. 2 the rim A is retained between side plates E on the rigid rim B so that side movement is positively prevented. The connections C may also be crisscrossed in the manner indicated to provide additional lateral support to the rim A. Cross bolts such as e may be used to connect the side plates E together, such bolts being placed just clear of the rim A when the latter is fully compressed at the point of

support of the wheel. The side plates E are of course securely fixed upon the rim B by bolts or otherwise.

The rim A as shown in Figs. 1 to 6, is 5 preferably made up of a resilient strip coiled upon itself, the convolutions being separated by thin layers α of protective material such as tarred canvas so that the metal surfaces are kept from contact. By this arrangement 10 no irregularity, due to the thickness of the spring strip, is introduced except at the ends, but as that thickness is very small in proportion to the diameter of the rim, this does not introduce any appreciable inequality 15 in the resiliency at any point. Or, the rim may be built up by means of a number of round strips lying one over the other, as illustrated in Fig. 7, or flat strips as illustrated in Fig. 8 so arranged that their ends 20 shall not be situated at the same point of the circumference.

The tread or tire D may if desired, be of 25 stitched rope fiber as shown in Fig. 4, this being a material of known type and one which can be readily replaced when worn. It possesses however considerable strength 30 and wearing capacity and affords a good grip on the road so that skidding is practically impossible. It is moreover readily fixed on the rim, whereas india rubber cannot be securely attached direct to a metal surface. The flexible connections C allow 35 of free compression of the elastic rim but give strong tensional support. The tension is adjusted by any convenient means in order 40 to distribute the support equally around the wheel, the rigidity of the rim A depending to some extent upon the tightness of the connections C, which are always under tension except for a short distance at the bottom of 45 the wheel where the rim A is slightly flattened by the weight of the vehicle as shown in Fig. 1.

The arrangement shown in Figs. 3 and 45 differs from that of Fig. 2 in the fact that the guides E are dispensed with. The flexible connections C, which extend diagonally in side elevation are attached to the rims A and B by the clips a' and b' , respectively. 50 The clips a' are preferably in the form of rings of flat sheet metal encircling the sections of the rim A and provided with suitable means for engaging the connections C. The guides of Fig. 2 are not essential to the 55 efficiency of the wheel but may be provided as an additional protection against side strains on the rim. To regulate the tension of the flexible connections the clips b' are shown with adjusting screws which engage 60 nuts connected with the flexible connections C. In addition to the flexible connections E flat thin steel bands such as C' are provided, placed between the connection C, and passing alternately to and from the rims A and

B and staggered with respect to the connections C as shown in Fig. 3. The flat bands C' are sufficiently flexible not to interfere with the action of the rim A but owing to their width they give great lateral rigidity 65 to hold the rims in alinement during skidding of the wheel. Either of the two types of connections E and C' can be used independently of the other.

In the modification shown in Figs. 5 and 6 the lateral support for the rim A is given 70 by the ring b^2 on the periphery of the rim B, which ring is formed with guiding channels such as b^3 within which slide the guide plates a^2 secured at intervals to the clips a' . The flexible connections C are shown 75 connecting together the edges of the two rims without crossing.

Fig. 7 shows a type of rim A which is built 80 up of wire coiled into circular form, the convolutions being bound together in any 85 suitable manner such as by bands or the like, and thus united into a solid but resilient rim. Several wires may be used, their ends being shown at a^3 , but a single long wire may be 90 employed.

Fig. 8 shows a modification of the rim A in which steel bands are reduced in width 95 toward the outside of the rim so as to give a narrower tread and a rounded cross section to the rim. A continuous band may be employed forming a single coil, or separate bands may be used the ends of which are shown at a^4 .

What I claim and desire to secure by Letters Patent of the United States is:— 100

1. An improved resilient wheel comprising an inner rigid rim, an outer rim formed of resilient laminations, clips for binding said laminations together, said clips being each provided with two laterally spaced engaging devices, corresponding sets of engaging devices carried by the inner rim, flexible connections spanning the space between the rims and attached to said engaging devices, and means for preventing lateral movement 110 of the rims.

2. An improved resilient wheel comprising an inner rigid rim, an outer rim formed of resilient laminations, clips for binding said laminations together, said clips being each provided with two laterally spaced engaging devices, corresponding sets of engaging devices carried by the inner rim, flexible connections spanning the space between the rims and attached to said engaging devices, adjusting members connected with one set of engaging devices to vary the tension on the flexible connections, and means for preventing lateral movement 120 of the rims.

3. An improved resilient wheel comprising an inner rigid rim, an outer rim formed of resilient laminations, clips for binding

said laminations together, said clips being each provided with two laterally spaced engaging devices, corresponding sets of engaging devices carried by the inner rim, flexible 5 connections spanning the space between the rims and attached to said engaging devices, and a metal band positioned between the flexible connections and having convolutions

engaging the inner and outer rims to prevent lateral movement of said rims. 10

In testimony whereof I affix my signature in presence of two witnesses.

REINHART VICTOR WAGNER.
